AUTOMOBILE LAMP

Charles F. Gitschlag, Jr., Detroit, Mich.

Application September 2, 1955, Serial No. 37,764

Term of patent 7 years

(Cl. D48—32)

Fig. 1 is a perspective view of an automobile lamp showing my new design;

Fig. 2 is a side elevational view thereof;

Fig. 3 is a front elevational view thereof; and

Figs. 4 and 5 are sectional views taken on the lines 4—4 and 5—5 of Fig. 3.

The characteristic features of my design reside in the portions shown by means of full lines in the drawings.

I claim:

The ornamental design for an automobile lamp, substantially as shown and described.
